CLIMBING AND DIVING TOY

Logan L. Mallard, Norfolk, Va.

Application November 2, 1933, Serial No. 696,420

14 Claims. (Cl. 46—40)

This invention relates to new and useful improvements in toys and more particularly to what may be termed a climbing and diving toy, the primary object of the invention being to provide a new and novel movement for conveying an object vertically and horizontally and discharging the same substantially in the manner of a dive.

5 A further object of the invention resides in the provision of a structure in the appearance of a ladder with means in conjunction therewith for conveying an object upwardly thereon.

10 Still another object resides in providing a movement in connection with the ladder aforesaid which will progressively dispose an object vertically thereon in the manner of walking.

15 Still another object of the invention resides in the provision of a structure for movement of the object vertically comprising stationary and movable rack bars arranged in opposed relation so that the movable rack bar may dispose the object step by step vertically on the stationary rack bar.

20 Still another object of the invention resides in the provision of specific means for converting vertical movement of an object to horizontal movement.

25 A still further object resides in the provision of means for releasing a display member to announce the subsequent discharge of the object from the device.

30 A further object resides in providing a device which is comparatively simple in structure, inexpensive to manufacture and one which will prove interesting to persons of all ages.

35 With these and numerous other objects in view, my invention consists in the novel features of construction, combination and arrangement of parts as will be hereinafter referred to and more particularly pointed out in the specification and

40 claims.

In the accompanying drawings forming a part of this application:

Figure 1 is a side elevation of my improved toy constructed in accordance with my invention;

45 Figure 2 is a front elevation thereof;

Figure 3 is a vertical longitudinal sectional view on an enlarged scale taken on line 3—3 of Figure 6 and showing more specifically the construction of the upper portion of the toy, the rack parts being shown in their normal position;

50 Figure 4 is a similar view showing the moving parts of the toy near the end of their reciprocatory motion;

55 Figure 4a is a fragmentary sectional view show-

ing the reciprocating rack bars at the extreme position they assume when advancing the toy;

Figure 5 is a detailed front elevation of one of the figures used in connection with my improved toy;

5 Figure 6 is a horizontal sectional view taken on the line 6—6 of Figure 3;

Figure 7 is a transverse vertical sectional view on lines 7—7 of Figure 3 and Figure 6;

10 Figure 8 is a fragmentary transverse vertical sectional view taken substantially on line 8—8 of Figure 1;

15 Figure 9 is a similar view showing the parts in a position which is assumed after the arms of the toy have actuated the bell crank lever;

Figure 10 is a fragmentary longitudinal sectional view taken substantially on line 10—10 of Figure 8 and showing more specifically the bell crank lever and its actuating bar;

20 Figure 11 is a fragmentary side elevation of the lower portion of the toy showing more specifically the actuating means thereof;

Figure 12 is a vertical longitudinal sectional view taken on line 12—12 of Figure 13;

25 Figure 13 is a horizontal sectional view taken on the line 13—13 of Figure 11;

Figure 14 is a horizontal sectional view taken on the line 14—14 of Figure 1;

30 Figure 15 is a section as seen on the line 15—15 of Figure 16; and

Figure 16 is a horizontal section as seen on the line 16—16 of Figure 15.

35 In describing the invention, I shall refer to the drawings in which similar reference characters designate corresponding parts throughout the several views and in which 1 designates a base of any preferred shape or size, upon which is mounted a standard 2 of any preferred size, shape or height, being preferably formed in sections and interlocked detachably by means of a male 40 and female joint designated by the numeral 3 and held in position by the leaf-spring latch 4. Mounted on the upper section of the standard 2 is a platform or the like 5 which is arranged horizontally which, for the purposes of describing 45 the type of toy disclosed, may be said to be a diving platform.

40 Mounted on the platform 5 and projected vertically therefrom are the uprights 6 which may be secured in any preferred manner to said platform, the upper ends of said uprights being 50 formed into channel shaped guides 7 which are arranged parallel to the platform 5. These channel guides 7 are braced at their one end to the 55

uprights 6 by means of the ornamental bracing arms 8.

Extending parallel and in spaced relation forward of the standard 2 is a ladder 9 which is also formed preferably in sections and held detachably together by means of the joint 10 similar to the joint 3 in connection with the standard 2. This ladder 9 is supported on the standard 2 by means of the lateral supporting arms 11. The sides of the ladder member 9 are bent to form channel shaped portions 12, as clearly shown in Figures 4 and 14 of the drawings, said channel members 12 corresponding to the channel members 7. The upper portion of the ladder member 9 is braced to the adjacent end of the horizontal channel shaped guide 7 by means of ornamental arms 13 similar to the arms 8, previously described.

As stated in the objects of the invention, it is an essential purpose to provide a movement which will advance an object vertically up the ladder and then transmit the same horizontally across the platform 5. In carrying out this idea, the one edge of each of the channel members 12 is bent inwardly and formed with plurality of spaced teeth 14 forming substantially a stationary rack bar. The outer edge of the rack bar between each of the teeth 14 is compoundly curved as shown at 15 for a purpose to be hereinafter and more particularly set forth. For purposes of simplicity, the portions of the device bearing the teeth 14 will be hereinafter referred to as stationary rack bars.

The upper edge of each of the channel shaped guides 7 is inwardly bent and formed with spaced teeth 16 similar to the teeth 14 and the edges of the flange in which said teeth are formed are also shaped as the edges 15 heretofore described. The flanges of the guides 7 in which the teeth 16 are formed may be said to be stationary horizontal rack bars and the same are riveted, soldered or otherwise secured at their ends to the upper ends of the vertical portions of the ladder 9.

Mounted for reciprocation in each of the channel shaped portions 12 of the ladder 9 is a movable rack bar 17 which is provided with teeth similar to the teeth 14 on the stationary rack bar. The movable or reciprocating rack bar 17 has its teeth opposed to the teeth 14 of the stationary rack bar, as clearly shown in Figures 3 and 4 of the drawings and it may be here stated that movement of the bar 17 is such that any element supported on the teeth 14 of the stationary rack bar may be lifted and carried to the next succeeding set of teeth on the stationary rack bars. In other words, the movement or reciprocation of the movable bar 17 is for a distance slightly greater than the distance between any two teeth 14 of the stationary rack bar. The movable rack bars 17 are preferably formed in sections removably secured together as shown at 18. Of course, where ladders of shorter length are utilized, it may not be necessary to form the rack bars 17 and other elements in sections.

Mounted in the channel shaped guide 7 for reciprocation therein is an additional rack bar 19, which is provided also with teeth similar to the teeth 16 with respect to which the teeth of the rack bar 19 are opposed. A bell crank lever 20 is fulcrumed on one of the arms or uprights 6, as clearly shown in Figures 3 and 4 of the drawings, one arm of which is loosely linked by means of a pin 21 to the rack bar 19 and the other arm of which is similarly linked by means of the pin 22 to the upper portion of the rack bar 17 carrying the teeth. Thus, when the vertically mov-

able rack bar is actuated in its guide, the horizontally disposed rack bar 19 will be actuated in its guide rack 7. Two bell crank levers are, of course, provided, one on each side of the platform 5 so that both horizontally disposed rack bars 19 may be actuated simultaneously with the actuation of the two vertically movable rack bars 17.

In order that the object which is being conveyed on the teeth 14 and forwardly on the teeth 16 of the stationary rack bars may not casually drop therefrom, means is provided to cause the movable rack bars 17 and 19, respectively, to be yieldingly held adjacent the stationary rack bars. To this end, a plurality of spring members 23 are provided on the ladder 9, as clearly shown in Figure 14 of the drawings, the ends of said spring contacting with the edges of the movable rack bars 17 to hold the latter in yielding contact with the end walls of the channel shaped guide 12.

Similarly, a series of springs, as disclosed by the numeral 24 and 25 are provided in connection with the guide 7 acting on the movable rack bar 19 to hold the latter in contact yieldingly with the upper wall of the guides 7. In this manner, locking pockets are formed between the teeth of the stationary and movable rack bars, as clearly shown in Figure 3 of the drawings, whereby any element held therein may be prevented from displacement and obviously, when the movable rack bars 17 and 19 are actuated, said elements may be progressively moved upwardly and forwardly on the vertical and horizontal stationary bars.

I have provided means for reciprocating the movable rack bars. To this end, a forked lever 26 is fulcrumed as shown at 27 on the lower end of the standard 2, the arms of which are slotted and engaged with pins 28 projected respectively from the lower ends of the rack bars 17, as clearly shown in Figures 11 and 13 of the drawings. The handle portion of the lever designated by the numeral 29 may be grasped by the hand of the user and reciprocated manually to actuate the device but said handle is also slotted as shown at 30 so that it may be connected with any source of power so that the device may be automatically actuated. Pins 31 extend laterally from the sides of the standard 2 adjacent the lower end thereof to limit the rocking movement of the lever 26 downwardly, this being clearly shown in Figures 1 and 11 of the drawings, as well as in Figure 13. Of course, these pins are located so that a predetermined relation of the teeth of the movable rack bars with respect to the stationary rack bars may be obtained. The upward movement of the rack bars 17 is limited by contact of the upper ends thereof with the upper walls of the channel shaped guide racks 7, although other means for limiting this upward movement may be provided if desired.

Obviously, a bar or pin may be carried vertically upward on the stationary rack bar having the teeth 14 through the actuation of the movable rack bar 17 and when said bar or pin reaches the uppermost tooth 14 on the stationary rack bar vertically arranged, the same may be carried horizontally across the rack bar 18 through the medium of the horizontally disposed and reciprocating rack bar 19. This relationship between the parts is clearly disclosed in

Figures 3, 4, 8 and 9 of the drawings. While I have described this invention as particularly

applicable to toys, it will be understood that the mechanical movement is considered to be sufficiently novel to warrant application thereof to other uses. For illustration, in use as a toy, I have provided a figure for movement vertically and horizontally on the device. This figure comprises a body 32 having a head 33 thereon and a pair of pivoted arms 34. The outer ends of the arms are somewhat spherical as shown at 35, simulating hands, and support a horizontally disposed pin or bar 36. A pair of pivoted legs 37 are provided formed with feet 38 thereon. Plates 39 which extend upwardly from the feet project forwardly from the lower ends of the legs 37 above forward portions of the feet as shown in Figure 4 so that said feet will not engage the rungs of the ladder 9 when the figure is moved vertically of the device. This figure is adapted to be placed in relation to the device so that the cross bar or pin 36 is supported on the teeth 14 to be moved step by step or tooth by tooth up the stationary rack bar through the medium of the reciprocation of the movable rack bar 17.

In order to position the cross bar 36 of the figure so as to be initially engaged by the movable rack bar 17, the walls of the channel members 12 of the ladder 9 at the lower end thereof are shaped to form a mouth 40, the walls of which support the pin 36 until such time as the lowermost tooth of the movable rack bar 17 engages the same and moves said pin upwardly to be received on the lowermost tooth of the stationary rack bar. This mouth construction is clearly shown in Figure 12 of the drawings.

Obviously, as the rack bars 17 are reciprocated, the cross bar or pin 36 of the figure will be progressively moved, tooth by tooth up the stationary rack bar. The feet of the figure will be caused to contact with the rungs of the ladder 9 as shown in Figures 3 and 4 of the drawings, simulating the movement of a man up a ladder. As the pin or bar 36 is moved from one tooth 14 to the other on the stationary rack bar by action of the movable rack bar 17, said pin or bar will be caused to travel over the compoundly curved edges of the stationary rack bar between the respective teeth and the rack bar 17 will be caused to yield against the springs 23, as appears obvious. When the bar or pin 36, carrying the figure, reaches the uppermost tooth 14 of the stationary rack bar, it is adapted to be engaged by the horizontally movable rack bar 19. The end of said rack bar 19 which is adjacent the rack bar 17 is arcuately formed as shown at 41 in Figures 3 and 4 of the drawings. This arcuately formed end of the rack bar 19 permits the ends of the ladder to ride readily under the pin or bar 36 to permit the latter to be readily engaged with the first tooth of said rack bar 19 and thus carried progressively, tooth by tooth, along the stationary rack bar 16. As stated previously, the movement of the teeth of the movable rack bars 17 and 19 is slightly greater than the distance between the teeth of the stationary rack bars so that the bar or pin 36 of the figure is at all times progressed in its path from one tooth to the other without any difficulty whatsoever. When the pin of the figure reaches the outermost end of the horizontal and stationary rack bars, the same is discharged from the guide 7, giving an effect of diving from the platform 5. Various devices, as will be hereinafter referred to, may be utilized in connection with the discharge of the figure or element from the device.

To announce the subsequent discharge of the figure from the device, I have provided a means visible to the eye, which is thought to be effective in a toy of this character. To this end, I provide a pennant or banner 42, one end of which is supported on an angular plate 43 having an opening 44 therein. A keeper 45 is mounted on the lower portion of the platform 5 adjacent one side edge thereof and is slotted as shown at 46. The slot 46 registers with an opening 47 in the bottom of the platform through which is actuated a pin 48. The banner or pennant is rolled in the plate 43 and supported on the keeper 45 whereupon the pin 48 is disposed through the opening 47 and through the slot 46. This retains the banner or pennant in rolled position on the device as shown in Figure 8 of the drawings. The pin 48 is carried on one end of a bell crank lever 49, the latter being fulcrumed as shown at 50 on one of the uprights 6 (as shown in Figure 10 of the drawings). The other arm of the bell crank lever 49 is in the path of the pin 36 as it is moved across the horizontal rack bar. When the pin 36 contacts with the one arm of the bell crank lever, the latter is rocked, raising the pin 48 upwardly and releasing the banner to a flying position. The other end of the banner or pennant is connected through the medium of a flexible connection 51 with a support 52 projecting from the lower outer end of the platform 5. As stated, upon the releasing of the banner or pennant, visible announcement is made of the event of discharge of the element from the device. This announcement is made a short period of time prior to the projection or discharge of the figure from the toy.

Also as an attractive feature of the toy, the one end of the bell crank lever 20 is provided with sockets as shown at 53 for the support of staffs 53' carrying pennants or the like. These pennants may be substituted with other devices, if desired, but in any event, some element may thus be provided which will reciprocate as the device is operated. Any visible means provided in the sockets 53 will be attractive to the eyes of those operating the invention.

As previously stated, the figure supported on the cross bar or pin 36 is discharged from the device with somewhat of a diving action. Any means may be provided in association with the end of the platform 5 to create a different effect as for instance, a slide so that the figure when discharged will be caused to descend thereon to any other element or to the floor. I have shown, however, an element designated by the numeral 54 representing a tank into which the figure is adapted to dive when discharged. This element 54 is in the form of a stand over which is disposed an elastic covering 54'. The arrows disclose the discharge of the figure from the platform and the rebound thereof from the covering 54'. This is only one illustration of what might be accomplished in connection with the discharge of the figure from the toy.

From the foregoing description of the construction of my improved device, the operation thereof will be readily understood and it will be seen that I have provided a simple, inexpensive and efficient means for carrying out the objects of the invention.

While I have particularly described the elements best adapted to perform the functions set forth, it is obvious that various changes in form, proportion and in the minor details of construction may be resorted to, without departing from

the spirit or sacrificing any of the principles of the invention.

Having thus described the invention, what is claimed is:

- 5 1. A toy device comprising a frame including
a vertical guideway terminating in a horizontal
guideway, a separable member adapted to be
carried through said vertical and horizontal
guideways and reciprocating means for ad-
vancing said member continuously through said
vertical and through said horizontal guideways.

10 2. A toy device of the class described comprising
a frame including a vertical guideway termin-
ating in a horizontal guideway, a separable
15 member adapted to be carried through said ver-
tical and horizontal guideways and reciprocating
means for intermittently advancing said mem-
ber in continuous motion through said vertical
and through said horizontal guideways.

20 3. In a toy of the class described, a frame, a
separable member, means for advancing said
member on said frame in a step by step move-
ment, and signaling means movably connected
25 to said frame and actuated by said advancing
means for visibly indicating the progress of ad-
vance of said member on said frame.

30 4. In a toy of the class described, a frame
vertically arranged and formed with spaced
apart teeth on opposite sides thereof, a pin
35 loosely supported on the teeth of said frame and
having a body suspended therefrom between the
sides of said frame, and reciprocating means for
advancing said pin to successive teeth through-
out the length of said frame.

40 5. A toy device of the class described, comprising
a pair of spaced apart stationary rack bars
having teeth spaced one from the other, a body
carrying pin loosely supported on the teeth of
45 said spaced bars, means for successively advanc-
ing said pin on the teeth of said bars and addi-
tional means coacting with the last mentioned
means for discharging said pin in a direction an-
gular to the plane of said bars.

50 6. A toy device of the class described, comprising
a frame formed with parallel spaced apart
rack bars, the teeth of said bars being spaced,
one from the other, a separable member support-
able on the teeth of said rack bars, reciprocating
55 means for advancing said member on the teeth
of said bars successively and additional recipro-
cating means coacting with said last mentioned
means for advancing and discharging said mem-
ber in a plane angular to the plane of said rack
bars.

60 7. In a toy of the class described, a frame hav-
ing portions thereof formed with spaced apart
channels, one wall of each of said channels being
toothed to provide a pair of spaced stationary
tooth bars, a separable member loosely support-
65 able on the teeth of said bars and means support-
able and reciprocable in said channels for ad-
vancing said member successively on the teeth
of said bars.

70 8. In a toy of the class described, a frame hav-
ing portions thereof formed with spaced apart
channels, one wall of each of said channels being
toothed to provide a pair of spaced stationary
tooth bars, a separable member loosely support-
75 able on the teeth of said bars and reciprocating
means yieldingly supported in said channels, co-
operating with said rack bars and member to
advance the latter tooth by tooth on said bars.

9. In a toy of the class described, a frame
having portions thereof formed with spaced apart
channels, one wall of each of said channels be-

and supportable loosely thereon, said pin having a body member suspended therefrom, a pair of additional and reciprocating rack bars movably supported within said channel members, said reciprocating rack bars having teeth thereon similar to the teeth of the first mentioned rack bars and arranged opposite to the latter, yielding

means within said channel members acting on said reciprocating rack bars tending to normally retain the latter in a predetermined position within said rack bars, and means for actuating said reciprocating rack bars to advance said pin tooth by tooth on the first mentioned rack bars. 5

LOGAN L. MALLARD.
